FLOOR FOR REFRIGERATOR CARS

Charles D. Bonsall, Pittsburgh, Pa., assignor, by
mesne assignments, to Standard Railway
Equipment Manufacturing Company, a corpo-
ration of Delaware

Application April 22, 1937, Serial No. 138,299

15 Claims. (Cl. 189—34)

The invention relates to railway refrigerator cars which are used to transport perishable commodities, such as fruits, vegetables, fish, candies, flowers, etc., and more particularly to a floor construction thereof, and has for its object to provide a very efficient, strong and light floor construction which is economic to manufacture and easy to build in the car.

Formerly ice was confined in an ice basket 10 in the bunker of a railway refrigerator car and the lading was cooled by circulation of air around the ice and between the perishable commodities in the lading compartment, and the water from the melting ice was trapped and drained to the exterior of the car so that it was impossible for the water to damage the insulation of the car. In recent years, however, it has become common practice to put cakes of ice on top of the perishable commodity containers after they are loaded in the car. Some fresh vegetables and ferns are frequently loaded in the car by alternating layers of such vegetables (or ferns) with layers of cracked ice. Perishable commodities are also preserved by blowing pulverized ice over and between the packages after they are loaded in the car. These and other methods of cooling where the ice is in contact with the lading result in considerable water in the car. (Cars are sometimes precooled by putting cakes of ice in the car and closing the doors and allowing the ice to melt. Condensation (or sweating) also causes moisture in a car.) If the water is allowed to contact the insulation the insulating value thereof would be decreased, and one of the principal objects of this invention is to prevent the water from destroying or reducing the efficiency of the insulation.

Another object is to protect the floor insulation by covering it with a plurality of metallic sheets and providing means to weld the margins of adjacent sheets together from the inside of the car while the metallic sheets are in place in the car without igniting the floor insulation, and whereby the welded material 40 may be burned off without igniting the floor insulation when it is desired to remove a metallic sheet for replacement. Welding the sheets together provides a waterproof joint which prevents water in the car from coming in contact with the floor insulation.

Another object is to provide a beam at the meeting edges of adjacent sheets and welded material securing the adjacent sheets together and to the beam, which beam provides protecting walls between the line of welding and the

floor insulation to protect the insulation from the heat and drops of molten metal while the sheets are being welded together. This beam also provides a space (or spaces) between the line of weld and the walls of the beam to protect the floor insulation from the heat of the welding process.

Another object of the welded metallic sheet floor covering is to prevent infiltration of air from below the car to the inside of the car. 10 A railway car in motion causes considerable movement of air between the car and the roadbed.

While the invention is shown applied to the floor of a railway refrigerator car it may be used 15 in an insulated wall, such as side wall, end wall, roof or door of a railway car or automotive truck.

In the drawing:

Fig. 1 shows a typical application of my device 20 to a floor of a railway refrigerator car.

Figs. 2-5 inclusive show modified structures.

Fig. 6 is an enlarged drawing showing the joint between adjacent floor sheets of Fig. 1.

The drawing shows the usual parts of the 25 car, such as side sill 1; side wall sheathing 2; side wall lining 3; side wall insulation 4; side wall framing 5; upper wooden flooring 6; subflooring 7 and floor insulation 8.

A plurality of light weight metallic sheets 10 30 are laid over the floor 6 to protect the floor insulation 8 from moisture within the car and also protect the upper flooring against abrasion and means are provided to weld the adjacent margins of adjacent sheets together from the 35 inside of the car without disturbing the floor insulation and without disturbing the wooden flooring.

In the preferred construction the metallic sheets have depending marginal flanges 12 and 40 the channel member 13 straddles the marginal flanges 12 and the opposite walls 14 of the channel member are spaced apart from the flanges 12 to provide air spaces therebetween to protect the insulation and the wooden flooring from 45 the heat of welding. Welded material 15 is applied at the junction of the body of the sheets with the flanges 12 to secure the sheet together. The channel member is preferably provided with 50 flanged parts 17 engaging and supporting the body portion of the metallic sheets.

The upper wooden flooring 6 may or may not be used. When such wooden flooring is used the sheets may be relatively light material and the channel members 18 may be shallow and 55

let into the wooden flooring, as shown in Fig. 3. When the wooden flooring is not used the metallic sheets may be of relatively heavy material and the channel members may be positioned 5 closer together, and deeper, as shown in Fig. 1.

Fig. 3 shows the welded material also securing the flanges 19 to the channel member 18.

In the modification shown in Fig. 2 the channel 20 member straddles and snugly fits the flanges 21 of the metallic sheets so as to hold them in place and the channel members are

provided with outwardly flared opposite walls 22 to provide air spaces 23 between these walls 22 and the welded material 24.

15 In the modification shown in Fig. 4 the channel member 30 has converging side walls 31 which fit into a fan tail groove in the wooden flooring 6 and held in position thereby.

In the modification shown in Fig. 5 a hollow

20 member 35 is used having a flat side formed with an inwardly projecting groove 37 and both of the sheets 38-39 engage and are supported by the flat portions 40-41 of the hollow member 35 and each sheet has a marginal flange

25 43 projecting into the groove. Welded material 44 secures the flanges to a portion of the hollow member and the welded material also preferably secures the flanges together. The marginal flanges 43 of the sheets are preferably

30 spaced apart from the sides 46 of the groove to provide spaces 47 between the side 46 and the welded material 44.

In the form shown in Fig. 5 the hollow member is formed from a metallic plate formed with

35 an inwardly projecting corrugation with flat portions on opposite sides thereof. The means of connecting the metallic sheets together (and preferably also to the hollow member) are preferably within the groove so as to provide a

40 smooth upper surface of the floor.

The accompanying drawing illustrates the preferred form of the invention, though it is to be understood that the invention is not limited to the exact details of construction shown 45 and described, as it is obvious that various modifications thereof, within the scope of the claims, will occur to persons skilled in the art.

I claim:

1. A car wall comprising two metallic sheets, 50 insulation on one side of said sheets and means to weld said sheets together from the other side of the sheets without igniting the insulation, said means comprising a hollow member imbedded in the insulation having a flat side with a groove therein, each of said sheets engaging said flat side and having a marginal flange projecting into said groove and welded material securing said flanges to the member within the groove.

60 2. A car wall comprising two metallic sheets, insulation on one side of said sheets and means to weld said sheets together from the other side of the sheets without igniting the insulation, said means comprising a hollow member imbedded in the insulation having a flat side with a groove therein, each of said sheets engaging said flat side and having a marginal flange projecting into said groove and welded material securing said flanges together and to the member 70 within the groove.

3. A car wall comprising two metallic sheets, insulation on one side of said sheets and means to weld said sheets together from the other side of the sheets without igniting the insulation, 75 said means comprising a hollow member im-

bedded in the insulation having a flat side with a groove therein, each of said sheets engaging said flat side and having a marginal flange projecting into said groove and welded material securing said flanges to the member within the groove, said marginal flanges being spaced from the side walls of the groove.

4. A car wall comprising two metallic sheets, insulation on one side of said sheets and means to weld said sheets together from the other side 10 of the sheets without igniting the insulation, said means comprising a hollow member imbedded in the insulation formed from a metallic plate and having a flat side formed with an inwardly projecting corrugation, each of said sheets engaging said flat side and having a marginal flange projecting into said corrugation and welded material securing said flanges to the corrugation.

5. A car wall comprising two metallic sheets 20 having adjacent marginal contacting flanges, insulation on the flange side of the sheets, and means to secure said sheets together from the opposite side of the sheets from the insulation, said means comprising a channel member straddling said sheet flanges and provided with opposite walls spaced apart from said sheet flanges to provide air spaces therebetween, and welded material securing said flanges together and to said channel member.

6. A floor for a refrigerator car comprising a wooden flooring, insulation below the wooden flooring, a channel member let into said flooring, two metallic sheets resting upon said flooring and having adjacent marginal flanges positioned within said channel member, and welded material securing said flanges together and to said channel member, whereby the member and the flooring protect the insulation from the heat of the welding process.

7. A floor for a refrigerator car comprising a wooden flooring, insulation below the wooden flooring, a channel member let into said flooring, two metallic sheets resting upon said flooring and having adjacent marginal flanges positioned within said channel member and spaced horizontally from the walls of the channel member to provide spaces therebetween, and welded material securing said flanges together, whereby the member and the flooring protect the insulation from the heat of the welding process.

8. A floor for a refrigerator car comprising a wooden flooring, insulation below the wooden flooring, a channel member having converging side walls fitting into a fan tail groove in said 55 flooring, two metallic sheets resting upon said flooring and having adjacent converging marginal flanges positioned within said channel member, and welded material securing said flanges together, whereby the member and the flooring protect the insulation from the heat of the welding process.

9. A car wall comprising two metallic sheets having adjacent marginal flanges, insulation on the flange side of the sheets, said sheets being 65 welded together from the opposite side, and means to protect said insulation from the heat of welding, said means comprising a channel member straddling said flanges and provided with opposite walls spaced apart from said flanges to provide air spaces therebetween, said walls 70 engaging the body portions of said sheets.

10. A car wall comprising two metallic sheets having adjacent marginal flanges, insulation on the flange side of the sheets, said sheets being 75

welded together from the opposite side, means to protect said insulation from the heat of welding, said means comprising a channel member straddling said flanges and provided with opposite walls spaced apart from said flanges to provide air spaces therebetween, and means to secure said sheets to said member.

5 11. A floor for a refrigerator car comprising a wooden flooring, insulation below said flooring, a channel member let into said flooring, two metallic sheets resting upon said flooring and having adjacent marginal flanges positioned within said channel member and spaced horizontally from the walls of the channel member 10 to provide spaces therebetween, and welded material at the juncture of the sheets and flanges to secure the sheets together whereby the member and the wooden flooring protect the insulation from the heat of the welding process.

15 12. A car wall comprising two metallic sheets having adjacent marginal flanges, insulation on the flange side of the sheets near said flanges, and means to secure said sheets together from the opposite side of the sheets from the insulation 20 without igniting said insulation, said means comprising a channel member straddling said sheet flanges and provided with opposite walls spaced apart from said sheet flanges to provide air spaces therebetween, said walls engaging the body portions of the wall sheets and welded material applied at the juncture of the sheets and the flanges to secure the sheets together.

25 13. A car wall comprising two metallic sheets having adjacent marginal flanges, insulation on the flange side of the sheets near said flanges, and means to secure said sheets together from 30

the opposite side of the sheets from the insulation without igniting said insulation, said means comprising a channel member straddling said sheet flanges and provided with opposite walls spaced apart from said sheet flanges to 5 provide air spaces therebetween, said walls being provided with flanged parts engaging the body portions of the wall sheets and welded material applied at the juncture of the sheets and the flanges to secure the sheets together.

10 14. A car wall comprising two metallic sheets having adjacent marginal flanges, insulation on the flange side of the sheets near said flanges, and means to secure said sheets together from 15 the opposite side of the sheets from the insulation without igniting said insulation, said means comprising a channel member imbedded in the insulation and straddling and snugly fitting said flanges and provided with outwardly flanged opposite walls spaced apart from said sheet flanges to provide air spaces therebetween, said walls engaging the body portions of the wall sheets and welded material applied at the juncture of the sheets and the flanges to secure 20 the sheets together.

25 15. A car wall comprising two metallic sheets having adjacent marginal contacting flanges, insulation on the flange side of the sheets near said flanges, and means to secure said sheets together from 30 the opposite side of the sheets from the insulation without igniting said insulation, said means comprising a channel member straddling said sheet flanges and provided with opposite walls spaced apart from said sheet flanges to provide air spaces therebetween, and welded material securing said flanges together.
